UNITED STATES PATENT OFFICE.

GEORGE P. WIGGINTON, OF KALAMAZOO, MICHIGAN, ASSIGNOR, BY MESNE ASSIGNMENTS, TO REMINGTON RAND INC., OF NEW YORK, N. Y., A CORPORATION OF DELAWARE.

INDEX APPARATUS.

Application filed April 23, 1927. Serial No. 185,983.

The main object of this invention is to provide an improved index apparatus including a plurality of sheets or cards in a binder or holder in which the sheets or cards 5 may be conveniently manipulated for arrangement in stepped relation to display portions of each sheet or card, the arrangement of the cards in the binder or holder and removal therefrom being greatly 10 facilitated.

A further object is to provide a transfer means by means of which sheets or cards may be quickly arranged in sets and transferred as a set to a binder.

15 A still further object is to provide means whereby a selected card may be quickly introduced to or removed from a series or set of sheets without disarranging the remaining sheets.

20 Objects pertaining to details and economies of my invention will definitely appear from the description to follow. The invention is pointed out in the claims.

A structure which embodies the features 25 of my invention is clearly illustrated in the accompanying drawing forming a part of this application, in which:

Fig. 1 is a plan view of a temporary binder constituting one element of my improved apparatus with a partial set of sheets or cards therein, the transfer member being in position to receive a selected number of sheets.

Fig. 2 is a fragmentary end view of the 35 structure shown in Fig. 1 with certain of the sheets transferred to the transfer member.

Fig. 3 is a plan view of the transfer member with a plurality of sheets arranged therein.

40 Fig. 4 is a fragmentary perspective view of the transfer member illustrating the distinguishing color of alternate posts.

Fig. 5 is a fragmentary plan view of a series of sheets arranged in stepped relation, 45 one of the sheets necessary to make a continuous stepped series being omitted.

Referring to the drawing, in the embodiment of my invention illustrated I employ a binder of the prong type such as illustrated 50 in my application for Letters Patent filed February 14, 1927, Serial No. 168,009, and comprising generally a pair of back members 1, 1 hinged together at 2, each back member being provided with a set of curved

posts or prongs 3. When the binder is closed 55 these prongs interlap, being disposed out of alignment. Covers 4 are hinged to the back members.

The sheets or cards 5 are each provided with a plurality of uniformly spaced holes 60 6, all of the holes except the end ones of each sheet having associated therewith a colored area or portion 7 on the sheet so that when the sheets are arranged in stepped relation as shown in Fig. 3 none of the colored area 65 is exposed except on the top sheet. However, when the sheets are arranged in non-uniform stepped relation as shown in Figs. 1 and 5, portions of the colored area are exposed so that the eye readily detects the 70 non-uniform relation or that a sheet or card is missing from the series.

The holes of the several sheets being uniformly spaced, they are properly registered, 75 when the cards are arranged in this stepped relation. The posts 3 are spaced so that each sheet is engaged by two of the posts, thereby retaining the sheets in proper alignment.

To facilitate the engagement of the sheets on the posts and the removal of a group 80 of sheets to permit the insertion or removal of selected sheets, I provide a transfer bar 8 having a series of pins 9 thereon spaced in accordance with the spacing of the holes 6 of the sheets so that the sheets may be 85 engaged on the holders in stepped relation as shown in Fig. 3 and the entire group or set of sheets arranged on the holder transferred to the posts by bringing the ends of the pins into end to end engagement with 90 the posts.

The ends of the posts are tapered at 10 while the pins have corresponding recesses 11 facilitating the positioning of the pins in end to end relation to the posts and the 95 holding of the same in such relation.

To facilitate the arrangement of the sheets upon the pins, alternate pins are colored or formed of different colored material; for instance, one group of pins may be 100 nickled and the other brass or brass plated. This greatly aids in the arrangement of the sheets upon the pins as the operator slips a sheet first upon the plain post and then upon the colored post. One or more missing sheets is indicated by the exposure of 105 colored portions associated with the holes.

Other indicia than color might be em-

ployed in this relation, although the color serves as a very convenient index.

- This arrangement of pins of alternating colors or other distinguishing characteristics 5 also facilitates the positioning of the transfer member relative to the post when it is desired to remove a group of cards to permit insertion or removal of a card or sheet at the desired point.
- 10 I have illustrated and described my improvements in an embodiment which I have found very practical. I have not attempted to illustrate and describe other embodiments and adaptations which are possible as I believe this disclosure will enable those skilled 15 in the art to embody or adapt my improvements as may be desired.

Having thus described my invention what I claim as new and desire to secure by Letters Patent is:

1. The combination with sheets having a plurality of uniformly spaced holes adjacent one edge thereof and colored portions associated with their holes other than 25 their end holes, thereby facilitating their arrangement in uniform stepped relation, a binder comprising hingedly connected back members provided with curved sheet-engaging posts with pointed tips, and a transfer 30 bar provided with a plurality of pins having recesses in their ends adapted to receive the tips of the posts, said pins being spaced to correspond with the spacing of the holes in the sheets and alternate pins being of a distinguishing color to facilitate the arrangement of sheets upon the transfer bar and the presentation of the transfer bar to the posts.

2. The combination with sheets having a 40 plurality of uniformly spaced holes adjacent one edge thereof and colored portions associated with their holes other than their end holes, thereby facilitating their arrangement in uniform stepped relation, a binder comprising hingedly connected back members provided with curved sheet-engaging posts with pointed tips, and a transfer bar provided with a plurality of pins having recesses in their ends adapted to receive the tips of the posts, said pins being spaced to 50 correspond with the spacing of the holes in the sheets.

3. The combination with sheets having a 55 plurality of uniformly spaced holes adjacent one edge thereof, a binder comprising hingedly connected back members provided with curved sheet-engaging posts with pointed tips, and a transfer bar provided with a plurality of pins having recesses in their ends adapted to receive the tips of the 60 posts, said pins being spaced to correspond with the spacing of the holes in the sheets and certain pins being of a distinguishing color to facilitate the arrangement of sheets upon the transfer bar and the presentation 65 of the transfer bar to the posts.

4. The combination with sheets having a plurality of uniformly spaced holes adjacent one edge thereof, a binder comprising hingedly connected back members provided with curved sheet-engaging posts with 70 pointed tips, and a transfer bar provided with a plurality of pins having recesses in their ends adapted to receive the tips of the posts, said pins being spaced to correspond with the spacing of the holes in the sheets, 75 said bars being of a length exceeding the width of the sheets from top to bottom so that the sheets may be selectively engaged with the pins.

5. The combination with sheets having a 80 plurality of uniformly spaced holes adjacent one edge thereof and means associated with certain holes of each sheet facilitating the arrangement of the sheets in uniform stepped relation, a sheet holder provided with a plurality of uniformly spaced sheet-engaging posts, and a transfer bar provided with a plurality of pins selectively engageable end to end with said posts, said pins being spaced to correspond with the spacing of the 90 holes in the sheets and alternate posts being of a distinguishing color facilitating the arrangement of sheets upon the bar and the presentation of the bar to the posts.

6. The combination with sheets having a 95 plurality of uniformly spaced holes adjacent one edge thereof, a sheet holder provided with a plurality of uniformly spaced sheet-engaging posts, and a transfer bar provided with a plurality of pins selectively engageable end to end with said posts, said pins being spaced to correspond with the spacing of the holes in the sheets and alternate posts being of a distinguishing color facilitating the arrangement of sheets upon the bar and 100 the presentation of the bar to the posts.

7. The combination with sheets having a 110 plurality of uniformly spaced holes adjacent one edge thereof and means associated with certain holes of each sheet facilitating the arrangement of the sheets in uniform stepped relation, a sheet holder provided with a plurality of uniformly spaced sheet-engaging posts, and a transfer bar provided with a plurality of pins selectively engageable end to end with said posts, said pins being spaced to correspond with the spacing of the holes in the sheets.

8. The combination with sheets having a 120 plurality of uniformly spaced holes adjacent one edge thereof, a sheet holder provided with a plurality of uniformly spaced sheet-engaging posts, and a separate transfer bar provided with a plurality of pins selectively engageable end to end with said posts, said 125 pins being spaced to correspond with the spacing of the holes in the sheets, said bars being of a length exceeding the width of the sheets from top to bottom so that the sheets may be selectively engaged with the pins. 130

9. The combination with sheets having a plurality of uniformly spaced holes adjacent one edge thereof whereby the sheets may be arranged in superimposed stepped relation with registering holes, a binder provided with binding members with which the sheets may be selectively engaged, and a transfer bar provided with a plurality of pins spaced to correspond with the spacing of the holes in the sheets, alternate pins of the holder having visual distinguishing means, the pins being recessed at their tips to receive the ends of the binding members. 55
10. The combination with sheets having a plurality of uniformly spaced holes adjacent one edge thereof whereby the sheets may be arranged in superimposed stepped relation with registering holes, a binder provided with binding members with which the sheets may be selectively engaged, and a transfer bar provided with a plurality of pins spaced to correspond with the spacing of the holes in the sheets, the pins being recessed at their tips to receive the ends of the binding members. 60
11. The combination with sheets having a plurality of uniformly spaced holes adjacent one edge thereof whereby the sheets may be arranged in superimposed stepped relation with registering holes, a binder provided with binding members with which the sheets may be selectively engaged, and a transfer bar provided with a plurality of pins spaced to correspond with the spacing of the holes in the sheets and selectively engageable end to end with the posts, alternate pins of the holder having visual distinguishing means. 65
12. The combination with sheets having a plurality of uniformly spaced holes adjacent one edge thereof whereby the sheets may be arranged in superimposed stepped relation with registering holes, a binder provided with binding members with which the sheets may be selectively engaged, and a separate transfer bar of a length exceeding that of the width of the sheets from top to bottom and provided with a plurality of pins spaced to correspond with the spacing of the holes in the sheets the pins exceeding in number the holes in the sheets and selectively engageable end to end with the posts. 70
13. The combination of a binder comprising a pair of hingedly connected back members provided with pointed sheet-engaging posts, and a transfer bar of a length exceeding that of the width of the sheets from top to bottom and provided with a plurality of pins having recesses in their outer ends adapted to receive the tips of the posts facilitating the selective positioning of the bar and the transfer of sheets from the posts to the pins and vice versa. 75
14. The combination of a binder provided with a plurality of sheet-binding members, and a separate holder of a length approximately that of the binder provided with a plurality of uniformly spaced pins adapted to be selectively presented end to end to said binding members to facilitate the transfer of the sheets from the binding members to the holder pins and vice versa. 80
15. The combination with sheets having a plurality of uniformly spaced holes adjacent one edge thereof and means associated with one or more holes of each sheet facilitating the arrangement of the sheets in uniform stepped relation by such indicia, and a holder for said sheets provided with a plurality of sheet-engaging members coacting with the holes of the stepped sheets. 85
16. The combination with sheets having a plurality of uniformly spaced holes adjacent one edge thereof and colored portions associated with their intermediate holes so that when the sheets are disposed in superimposed stepped relation with registering holes the determination of the uniformity of the stepped arrangement of sheets is facilitated, and a binder for said sheets provided with a plurality of posts spaced so that each sheet is engaged by more than one post. 90
17. A set of sheets having a plurality of uniformly spaced holes adjacent one edge thereof, and colored portions associated with all of their holes except their end holes, thereby facilitating the arrangement of the sheets in superimposed stepped relation with registering holes. 95
18. A set of sheets having a plurality of uniformly spaced holes adjacent one edge thereof, and means associated with one or more holes of each sheet, facilitating the arrangement of the sheets in superimposed stepped relation with their holes in registering relation. 100
- In witness whereof I have hereunto set my hand. 105
- GEORGE P. WIGGINTON.

CERTIFICATE OF CORRECTION.

Patent No. 1,719,412.

Granted July 2, 1929, to

GEORGE P. WIGGINTON.

It is hereby certified that error appears in the printed specification of the above numbered patent requiring correction as follows: Page 3, line 84, claim 16, beginning with the word "intermediate" in line 84, strike out all to and including the word "facilitated" in line 88, and insert instead "holes other than their end holes, thereby facilitating their arrangement in uniform stepped relation"; and that the said Letters Patent should be read with this correction therein that the same may conform to the record of the case in the Patent Office.

Signed and sealed this 30th day of July, A. D. 1929.

(Seal)
